UNITED STATES PATENT OFFICE.

JOHN A. HAMILTON, OF HOMESTEAD, PENNSYLVANIA.

FOUNTAIN-PEN ATTACHMENT.

SPECIFICATION forming part of Letters Patent No. 716,224, dated December 16, 1902.

Application filed January 3, 1902. Serial No. 88,338. (No model.)

To all whom it may concern:

Be it known that I, JOHN A. HAMILTON, a citizen of the United States of America, residing at Homestead, in the county of Allegheny and State of Pennsylvania, have invented certain new and useful Improvements in Fountain-Pen Attachments, of which the following is a specification, reference being had therein to the accompanying drawings.

10 This invention relates to certain new and useful improvements in fountain-pen attachments, and has for its object the provision of novel means whereby the ordinary pen may be easily converted into a fountain-pen.

15 The present invention has for its further object to provide an attachment that may be easily placed in position and readily removed from engagement with the pen-point when desired.

20 My invention further contemplates to construct an attachment of the above-described character that will be extremely simple in construction, strong, durable, comparatively inexpensive to manufacture, and highly efficient in its operation.

25 The present invention still further aims to provide a novel form of attachment the forward end of which may constantly engage the under side of the pen-point, thus producing a certain movement of the attachment against the pen-point when the pen is in use that will automatically feed the pen-point and will serve to cut the dry ink that would otherwise tend to clog the pen.

30 My invention still further contemplates to provide an attachment that will form a reservoir under the pen-point, said attachment forming a contact with the under face of the pen at the rearward end of the attachment.

35 With the above and other objects in view the invention consists in the novel combination and arrangement of parts, to be herein-after more fully described, and specifically pointed out in the claim.

40 In describing the invention in detail reference is had to the accompanying drawings, forming a part of this specification, and wherein like numerals of reference indicate like parts throughout the several views, in 45 which—

Figure 1 is a perspective view of the pen, showing my improved attachment applied

thereto. Fig. 2 is a longitudinal vertical sectional view thereof. Fig. 3 is an under plan view of the pen-point and attachment. Fig. 4 is a perspective view of the attachment. Fig. 5 is a top plan view thereof. Fig. 6 is a side elevation of the same. Fig. 7 illustrates enlarged side elevations of the pen-point and attachment, showing the movements of the forward end of the attachment against the under face of the pen-point.

In the drawings the reference-numeral 1 represents a suitable penholder, and 2 the pen-point secured therein.

65 The reference-numeral 3 represents the attachment, carrying the semicircular portion 4 at the rear thereof, the contracted neck portion 5, and the downwardly-curving portion 6, which has tapering sides 7 and slightly-70 tapering walls 8, the latter tapering inwardly and terminating in the square nose 9, which square nose forms a contact with the under face of the pen. An air-space 10 is formed between the forward portion of the pen-point 75 and attachment, which, together with the opening 12, formed in the pen-point, will give proper vent to the reservoir.

80 The operation of my improved pen attachment is as follows: The pen is dipped into the ink in the usual manner, which will fill the reservoir, the ink flowing into the same through the openings 10 and 12. When the pen is in use, by exerting pressure upon the point of the same the square nose of the attachment will continuously serve to feed, and by the forward and rearward movement of the nose the clogging of the reservoir is prevented. Furthermore, in case the ink has become dry when the pen is not in use for a 90 considerable length of time the nose and forward end of the attachment will serve to cut the dry ink that may have accumulated during the inaction of the pen. When it has been found that the attachment has become worn 95 out or the material has lost its resiliency, a new attachment may be easily inserted in the penholder.

100 The many advantages obtained by the use of my improved attachment will be readily apparent from the foregoing description, taken in connection with the accompanying drawings.

It will be noted that various changes may

be made in the details of construction without departing from the general spirit of my invention.

Having fully described my invention, what I claim as new, and desire to secure by Letters Patent, is—

A device of the character described, comprising a single piece of resilient material having its front and rear portions extending

on a horizontal plane, a contracted neck portion, and a square forward end, as specified. 10

In testimony whereof I affix my signature in the presence of two witnesses.

JOHN A. HAMILTON.
